United States Patent Office

Des. 233,594

Patented Nov. 12, 1974

233,594

COMBINED FLUIDS CONTAINER AND APPLICATOR

Lowell T. Fears, Memphis, Tenn., assignor to D'Sal
Products, Inc., Memphis, Tenn.

Filed Dec. 20, 1972, Ser. No. 317,085

Term of patent 14 years

Int. Cl. D9—07

U.S. Cl. D9—10

FIG. 1

FIG. 3FIG. 2FIG. 4FIG. 5FIG. 1 is a front elevational view of a combined fluids container and applicator showing my new design;

FIG. 2 is a rear elevational view;

FIG. 3 is a left side elevational view, the right side being a mirror image thereof;

FIG. 4 is a top plan view thereof; and

FIG. 5 is a bottom plan view.

I claim:

The ornamental design for combined fluids container and applicator, as shown and described.
